GARMENT FINISHING AND FOLDING APPARATUS

James W. Steele, North Kansas City, Mo.

Application September 7, 1940, Serial No. 355,752

13 Claims. (Cl. 38—103)

This invention relates to garment finishing and folding apparatus, such as is required in connection with certain operations in various establishments like laundries and cleaning plants, shirt factories, etc., and the purpose of the invention is to improve and make more efficient the apparatus and operations involved in the finishing and folding of shirts and the like.

Accordingly one of the objects of my invention is to devise an improved construction in which all the necessary operations for both finishing and folding the garments may be carried out on one apparatus, and by the same operator occupying practically one and the same position throughout the combined finishing and folding process.

It is also sought to provide apparatus in which some of the operations involved in the process may be carried out substantially automatically, and in which the movements of the finishing operation cooperate to a certain degree in the carrying out of the remainder of the operations.

More specifically, the invention provides apparatus in which a garment finishing board is made a part of the same apparatus as that having the garment folding board, and is so coordinated therewith as to facilitate the performance of both the finishing and folding operations in the same working space, and with the finishing and folding boards cooperating in certain stages of those operations.

One important feature of the improved construction is the provision of band creasing means, for creasing and partly spreading or separating the ends of the bands used to wrap the garments, and to so arrange such creasing means as to produce the operation thereof entirely by the movements of the garment finishing board into and out of operative position.

Various other subordinate objects and improved features of construction also comprise a part of the purpose of my invention, as will be made to appear in the course of the following description thereof in connection with the accompanying drawings illustrating apparatus which I have found to embody satisfactorily an example of the proposed improvements—after which those features and combinations which are deemed to be both novel and patentable will be more particularly set forth and claimed.

In the drawings—

Figure 1 is a side elevation showing apparatus embodying the present improved construction, with dotted lines representing different opera-

tive positions of certain of the parts of said improved apparatus;

Figure 2 is a plan view of the same with part of the finishing board broken away;

Figure 3 is a sectional elevation, said view representing a section taken on the line 3—3 of Figure 1;

Figure 4 is an enlarged sectional detail view of a check or buffer device forming a part of the improved construction;

Figure 5 is an enlarged sectional detail view representing a section taken on the line 5—5 of Figure 3;

Figure 6 is a similar view representing a section taken on the line 6—6 of Figure 2;

Figure 7 is a perspective view of the top table portion of the apparatus and the fold board structure (omitting the movable finishing board member);

Figure 8 is a plan view of the same with said fold board in lowered position; and

Figure 9 is a similar view, illustrating another operative position assumed by the parts for carrying out the garment folding operation.

The present application relates to improvements in apparatus of the character illustrated in my pending application Serial No. 334,539 filed May 11, 1940.

Referring now to the accompanying drawings in detail, the improved construction is illustrated as comprising a pedestal member 10 having a base portion 6 and a top section 10' adjustably connected as indicated at 11 to the lower pedestal section 10. The top section 10' has an inclined top face having secured thereto (as by means of bolts 7) a cap plate 8 for supporting a table member 12 in correspondingly inclined position, as clearly illustrated in Figure 1—said table member being anchored to the cap plate 8 by means of screws 9 provided with spacing elements 9' at the front of the apparatus.

The structure of the table member 12 is in general similar to that forming a part of the apparatus covering by the aforesaid pending application, in that the same comprises a table having spaces or receptacle portions 14 for bands or other accessories and also a transverse channel or recess 15 for accommodating a supply of shirt wrapping bands 16 in convenient position beneath the folded shirt for facilitating the operator's grasping the same to wrap about the folded garment, as described in said application. The table member also carries guide strips or cleats 18 secured thereto by screws 17 and spaced apart the width of the folded shirt and formed

with inclined inner edges 19; and the table is also provided with a longitudinal recess 21 lined with material 22 of a suitable elastic or rubber composition (see Figures 7 to 9). At the rear of the table is provided a collar-shaped depression comprising a collar recess 24 having a collar block member 26 and also a collar engaging structure comprising an inclined lug 23 and the opposite side ledges 30 and secured in place by screws 27 or like.

Also at the rear of the recess 24 is hinged, at 33, a panel or fold board member 32 having folding arms 34 and 34' pivoted thereto at 35 and actuated by springs 36 normally into outwardly spread relation (see Figure 9) in the shirt folding operation as described in the pending application above referred to, and also adapted to fold inwardly into operative or shirt-folding position as represented in Figures 3 and 8. In this folding movement of the arms 34-34', the arm 34 is swung over the arm 34', and in this position said arms are latched by means of a sliding latch bar which is normally in a rearwardly retracted position whereby its forward end 42 (of upturned hook shape) is adapted to hook into latching engagement with the upper folding arm 34, as represented in Figures 1 to 3 and 8. The rear end 40 of the latch bar projects sufficiently for operative engagement with the top face of the table 12 (when the board 32 is raised as indicated by the dotted lines in Figure 1), whereby a forward sliding movement is imparted to the latch bar for the purpose of releasing the arm 34 from latching engagement with the forward end 40 of the bar, preparatory to removal of the shirt from the fold board 32.

Provision is also made for creasing and spreading the ends of the shirt-wrapping bands 16 which are stacked in the transverse recess or channel 13, for which purpose a channel member 58 is secured by screws 51 (Fig. 5) to the table opposite each end of said recess 15—each of said channel members having a block 52 of suitable elastic material such as rubber, and the arrangement being such as to leave the outer walls of the channel members projecting somewhat above the blocks 52 (see Figures 3 and 5), so that in the operation of creasing the bands, the ends of the bands will be bent or deflected upwardly as well as spread or fanned out to an extent adapted to facilitate the operator's selecting and taking hold of the bands only one at a time (see Figure 5).

The remainder of the creasing means in the present apparatus is constructed and arranged to embody the improvements and additional functions provided for by the present invention, which moreover eliminates some of the mechanism and certain operations necessary in the prior construction.

Accordingly in the present improved form of apparatus, the creasing elements comprise blades 56 which are pivoted at 57 in brackets 58 secured by screws 60 to the under face of a garment finishing board 62 in position for operative engagement of said plates with the wrapping bands 16 supported on the blocks 52 whenever said finishing board 62 is in its lowered operative position as shown in Figures 1 to 5. This finishing board 62 is of conventional padded construction (as indicated at 63) and is mounted for swinging movement from said lowered operative position rearwardly into its inoperative position as represented by the dotted lines in Figure 1. For adapting the finishing board for such swinging

movement, its rear portion is fastened by screws 64 to a frame piece 65 which is formed with end bearing portions 66 journaled upon the end of a transverse shaft 68 which is supported by projections 70 depending from the opposite rear portions or corners of the cap member 8.

One of said end bearing portions 66 of the frame 65 is formed with a rearwardly projecting arm 72 carrying a suitable counterweight 73, 10 while the other of said end bearing portions is also formed with an arm 74 pivotally connected by a suitable link 75 with the upper end of a treadle 16 fulcrumed at 77 at the floor level and having a tread portion 78 at the front of the apparatus, as illustrated in Figure 1.

There is also connected to said arm 74 a check or buffer device (see Figure 4) for cushioning the movement of the finishing board 62. This device is of substantially conventional form, 20 comprising a cylinder 80, plunger 81 and connecting rod 82 pivotally connected to said arm 74. The device is anchored for universal pivotal movement by means of an attachment 84 rigid with one end of said cylinder 80 and pivoted at 25 85 to a connection 86 which is in turn pivoted at 87 to the side of the pedestal. The device further includes an adjustable check valve element 88 adapted to regulate the exhaust port 90 and hence the stiffness of the buffer or checking action of the device with relation to the rearward movement of the finishing board into its inoperative position.

The front margin of the finishing board 62 is provided with a hook or latching member 94 adapted for engagement (through an opening 95 in the table 12) underneath the forward margin of the fold board 32—as illustrated in Figures 1 35 and 6. This hook member is rigid with a pivot bar 96 mounted in brackets 97 secured to the under face of the finishing board 62 at the front corners thereof, and connected by short spindles 98 with an outer bar or rail 100 which is adapted to rest upon the front margin of the table 12. This bar or rail 100 provides a handle member 40 extending the full width of the finishing board for operating the hook or latch element 95, and the weight of said bar or handle is sufficient to maintain said hook 94 normally in position 45 adapted for hooking or latching engagement with the fold board, as is shown in Figure 1.

As convenient accessories to the apparatus, a suitable receptacle 102 may be mounted on the rear of the finishing board 62 for holding a supply of collar supports in position conveniently available to the operator; and similarly, a holder 55 104 may be attached at the side of the pedestal (as by means of an arm 105 secured to one side margin of the table 12), for holding a supply of the shirt boards or stiffeners for use as required in the shirt folding operation.

60 The operation of the apparatus will be readily understood in the light of an understanding of the operation of the applicant's prior construction as outlined in the pending application referred to. Such operation may be here outlined briefly as follows.

65 The finishing operation is started with the finishing board 62 in lowered position, as shown in Figures 1 to 3. Such finishing operation is of the same general character as that followed with the type of apparatus shown in my Patent No. 1,941,234, dated December 26, 1933. On completion of this part of the operation, the operator removes the garment from the finishing board and depresses the treadle 16, thereby ele-

vating the finishing board into the inoperative position indicated by the dotted lines in Figure 1; and by this same operation the fold board 32 (being engaged by the hook member 85 and thereby latched to said finishing board) is simultaneously raised into the upright position indicated by the broken lines in said Figure 1. This leaves the top face of the table member 12 free for the carrying out of the operations on the shirt (which has just been finished on the finishing board 62) in preparation for the next step of the process, namely, the shirt folding operation, as outlined in my prior Patent No. 2,010,333, dated August 6, 1935, and also referred to in my pending application Ser. 334,539 above referred to. In that process the finished shirt is laid face down upon the table with its collar or neck-bank portion in the recess 24, and the operator inserts a collar support (taken from the holder 102) into the collar portion of the shirt and thereafter proceeds to straighten out the remainder of the garment upon the table surface ready for folding.

The operator now releases the fold board 32 by lifting the arm 100 to disengage the hook member 85 from the front edge of the fold board, which thereupon swings down upon the garment resting upon the table 12. While the fold board 32 was in raised position, the latch bar 42 was retracted by engagement with the top of the table 12, as previously explained, thereby releasing the arms 34 and 34', which immediately tend to open up under the action of their springs 36; and if a previously folded garment is still on the board 32, the slight initial movement produced by the springs (in said raised position of the board) is sufficient to effect and maintain this unlatched condition of the arms 34 and 34' so that (on removal of the garment as the board is swung back upon the table 12) said arms continue their outward swinging movement into the spread relation illustrated in Figure 9 and by the dotted lines in Figure 3. The operator then proceeds with the folding operation, which is substantially the same as described in said prior Patent No. 2,010,333, particularly as regards the use of the arms 34 and 34' for the folding of the opposite sides of the garment upon its central portion lying between the guide strips 18—the operator incidentally making use of a shirt stiffening board (taken from the holder or receptacle 104) and also lifting one of the shirt wrapping bands 16 from the recess or channel 15 and applying it to the folded shirt. In this folding operation the arms 34—34' are relatched by means of said latch bar 42 to preserve said folded condition of the garment while on the fold board 32.

On completion of said folding operation, the fold board is simply left in its horizontal position, with the folded garment thereon, and the operator grasps the frame 100 and pulls the finishing board 62 back down into horizontal operative position and finishes another garment thereon. Then the operator depresses the treadle and thereby elevates both the finishing and fold boards (they being latched together) into the positions illustrated by the broken lines in Figure 1 and thereupon proceeds with the positioning of the newly finished garment upon the table 12. As the next step the operator raises the rail or handle 100 and releases the fold board 32 and returns same back to its lower or operative position—at the same time removing the finished and folded shirt which was left

on the fold board, and thus allowing the arms 34 and 34' to again fly outward into their outwardly spread relation as indicated in Figures 3 and 9.

The process is now in the same phase as at the instant of the first release of said fold board 32; and the subsequent steps of the operation follow the same sequence as has been just outlined.

In each movement of the finishing board down upon the table, moreover, it is to be noted that, without any other operation or any attention on the part of the operator, the end portions of the shirt-wrapping bands 16 are creased and bent in a manner similar to that described in my copending application Ser. No. 355,751, filed September 7, 1940; that is, the creasing elements 56 automatically operate (under the pressure of the weight of the finishing board in the present construction) to crease or score said end portions of the bands and at the same time bend the same between the upper edges of the channel members 50, with the result that the ends of the bands are deflected upwardly into somewhat separated and fanned-out relation, for obviously facilitating the operator's taking hold of the bands and grasping only one of them at a time.

The improved construction therefore provides an apparatus having all the facilities for carrying out both the finishing and folding operations on the garments and including the creasing of the end portions of the shirt-wrapping bands, and all by the means of one apparatus; and therefore requires no change of the garments from one apparatus to another, or any shifting of the operator's position from one machine to another; for with the improved apparatus the operator simply remains in one position in front of one and the same machine throughout the complete process, from the start of the finishing operation to the completion of the folding operation.

Such a compact and self-contained unit of construction is made possible by the mounting of the finishing board as a part of the same apparatus as that having the fold board, so as to move into and out of operative position at just the right stages of the operation and without any interference with the other stages of the process; on the contrary, this feature of the construction is taken advantage of by causing the movement of the finishing board to cooperate in the carrying out of the other steps of the operation, as is apparent from the fact that in each of its upward movements the finishing board automatically picks up the fold board, together with the folded garment thereon, and thus retains said fold board and folded garment in an out of the way position during the next step involving the preliminary work of the succeeding folding operation. And again, the return movement of the finishing board further cooperates in the performance of the rest of the process by acting as a carrier for the band creasing means into engagement with the bands and also applying the working pressure necessary for the carrying out of the band-creasing function. Thus is brought about a saving of time and also of the extra effort otherwise required for the performance of this band-creasing function, as well as the elimination of any extra operating means for that purpose.

The provision for control of the movements of the finishing board is very efficient in all respects, and the connections, including the check

or buffer device 80, produce a very easy and practically noiseless operation. The control of the latching means for the fold board is also very simple and effective; and the framework 96—98—100, besides providing a very convenient manual as well as automatic means for latching the folding and finishing boards together and also releasing the fold board at the proper times, further serves to provide a smooth finish rail for the front margin of the table 12 over which to drape the garment at the various stages of the process.

The holders 102 and 104 also provide very convenient accessories for maintaining the necessary supplies of the collar supports and shirt boards in handy position for the use of the operator as needed—as in the application already referred to.

From the foregoing, therefore, it is apparent that a very practical and efficient form of apparatus has been devised for the carrying out of all the several objects of my invention, as above noted; and while the described means point out one very effective embodiment of the same, it is of course obvious that many changes or modifications may readily be made without departing from the essential principles and scope of the invention. It is accordingly my wish to be understood as reserving the right to make whatever changes may fairly be deemed to fall within the spirit and scope of my invention as defined by the appended claims.

Having thus described my invention, what I claim and desire to secure by Letters Patent, is:

1. Garment finishing and folding apparatus comprising, a table provided with a collar recess and guide pieces spaced apart approximately the width of the folded garment, a garment fold board movable into and out of cooperative relation to the working face of the table, and a garment finishing board also movable into and out of operative position overlying said fold board.

2. Garment finishing and folding apparatus comprising a table having its upper working face provided with a collar-shaped depression and spaced guide elements conforming approximately to the width of the folded garment, a garment fold board movable into and out of cooperative relation to the working face of said table, a garment finishing board also movable into and out of operative position overlying said fold board, and latching means for securing said boards together as the finishing board moves into its inoperative position.

3. Apparatus of the character described comprising a table having its upper working face provided with a collar-shaped depression and spaced guide elements conforming approximately to the width of the folded garment, a garment fold board having one end thereof hingedly mounted on said table and movable into cooperative relation to the working face of the table, and a garment finishing board hinged for movement about an axis adjacent and parallel to the hinge axis of said fold board for adapting said finishing board for movement into operative position overlying said fold board.

4. Apparatus of the character described comprising a supporting structure including a table having its upper working face provided with a collar-shaped depression and spaced guide elements conforming approximately to the width of the folded garment, a garment fold board and a garment finishing board hingedly mounted on said supporting structure for movement about

adjacent parallel axes into and out of operative positions one above the other, and releasable latching means for securing said boards together as they move to inoperative position.

5. Garment finishing and folding apparatus comprising a table having its upper working face provided with a collar-shaped depression and spaced guide elements conforming approximately to the width of the folded garment, a garment fold board and a garment finishing board both movable into and out of operative position, one above the other, relative to the surface of said table, and means under the control of the operator for raising said finishing board into its inoperative position.

6. Garment finishing and folding apparatus comprising a table having its upper working face provided with a collar-shaped depression and spaced guide elements conforming approximately to the width of the folded garment, a garment fold board and a garment finishing board movable into and out of operative positions, one above the other, relative to the surface of the table, means under the control of the operator for raising said finishing board into its inoperative position, and releasable latching means for securing said boards together for simultaneous upward movement as said finishing board is raised into its inoperative position.

7. Apparatus of the character described comprising a table having its upper working face provided with a collar-shaped depression and spaced guide elements conforming approximately to the width of the folded garment, a garment fold board movable into and out of operative relation to the working face of the table, a garment finishing board also movable into and out of operative position above the working position of said fold board, and latching means carried by said finishing board for securing said boards for movement together in unison as said finishing board is moved into its inoperative position.

8. Garment finishing and folding apparatus comprising a supporting structure including a table, a garment fold board and a garment finishing board hingedly mounted on said supporting structure for movement about adjacent parallel axes into and out of operative positions, one above the other, and a releasable latching member carried by the free end of said finishing board for securing said boards together for simultaneous movement into their inoperative positions, said latching member having a smooth bar providing a finish rail for the forward edge of the table when said boards are in their operative positions.

9. Apparatus of the character described comprising a table, a garment finishing board movable into and out of operative position with relation to the surface of the table, means providing a supply of garment-wrapping bands in position for applying the same to the finished garment, and band-creasing means rendered operative by the movement of said board into its operative position.

10. Apparatus of the character described comprising a table, a garment fold board and a garment finishing board both movable into and out of operative positions, one above the other, relative to the working face of the table, said table having means for accommodating a supply of garment-wrapping bands beneath said fold board, and means actuated by the movement of said finishing board into its operative position for creasing said bands.

11. Garment finishing and folding apparatus comprising a table, a garment fold board and a garment finishing board both movable into and out of operative positions relative to the table surface, one board above the other, means providing a supply of garment-wrapping bands in position for applying the same to the folded garment, and band-creasing means rendered operative by the movement of said finishing board into its operative position.

12. Garment finishing and folding apparatus comprising a table, a garment fold board and a garment finishing board both movable, one above the other, into and out of operative relation to the table surface, the top of said table having means for accommodating a supply of garment-wrapping bands underneath said fold board, and means carried by said finishing board for apply-

ing a creasing and bending action to the opposite ends of the bands as said finishing board moves into its operative position.

13. Garment finishing and folding apparatus comprising a table, a garment fold board and a garment finishing board both movable into and out of operative positions, one above the other, relative to the surface of said table, the top of said table having means for accommodating a supply of wrapping bands in transverse relation to and beneath said fold board, band-creasing elements carried by said finishing board, and channel elements in position for supporting the ends of said bands and cooperating with said creasing elements to crease and bend the ends of the bands on movement of the finishing board into its operative position.

JAMES W. STEELE.
